UNITED STATES PATENT OFFICE.

HOWARD P. STURGES, OF GLENELLYN, ILLINOIS.

BUILDING.

Application filed December 28, 1920. Serial No. 432,633.

To all whom it may concern:

Be it known that I, HOWARD P. STURGES, a citizen of the United States, residing at Glenellyn, in the county of Du Page and State of Illinois, have invented certain new and useful Improvements in Buildings, of which the following is a specification.

This invention relates to the construction and arrangement of buildings, but more particularly of such buildings as are intended for commercial purposes, and has for its primary object to provide a practical and advantageous construction which will permit automobiles to be driven under their own power to the various floors and there conveniently parked without interfering with the stores, offices or other places of business located on such floors.

Another object of the invention is to provide a winding driveway having a parking strip extending substantially longitudinally thereof and contiguous thereto to permit automobiles to enter the strip at any point along the driveway.

A further object of the invention is to provide a relative arrangement of the driveway, the parking strip, and the stores or offices on the various floors, whereby the parked automobiles will not obstruct the entrances to the stores or offices located on the driveway or the view of show-windows or display-stands of these stores from the driveway.

The rapid increase in the number of automobiles, particularly in the larger cities, has made necessary traffic regulations which either forbid entirely the parking of automobiles in the public streets in the more congested districts or have so limited the time in which an automobile may remain in these streets that automobile owners have either been prevented from driving to and from their places of business, or compelled to leave their cars at a remote garage.

In a building of my improved type, it is possible to park cars in the building in which the owner has an office, store, or other place of business, and there is practically no delay in entering or leaving this building.

An inclined driveway communicates with the various floors of the building, and the offices or stores have entrances on this driveway. A parking strip is provided along the edge of the driveway, so that a car may be turned from the driveway onto this strip at any point where there is an un-

occupied space. The many other features and advantages of the invention will be better understood from the following specification when considered in connection with the accompanying drawings showing a selected embodiment thereof, in which:

Fig. 1 is a floor plan of the first or street floor;

Fig. 2 is a floor plan of the second floor; 65

Fig. 3 is a floor plan of the seventh and all floors above;

Fig. 4 is a vertical section on the line 4—4 of Fig. 1;

Fig. 5 is a vertical section on the line 5—5 70 of Fig. 1;

Fig. 6 is a vertical section on the line 6—6 of Fig. 1.

Referring to the drawings, the building forming the invention is constructed with an outer wall 7 which consists of a front 8, a rear 9 and side walls 10 and 11. For the purpose of illustration, the walls 9 and 10 are assumed to abut on neighboring buildings, and the walls 8 and 11 to face on streets. A winding driveway 12 enters the building from the front and follows the wall 10 nearly to the rear thereof, where it turns and follows the rear wall, turns again near the wall 11 and follows this wall to the front of the building, where it again turns and follows the front wall to a point above the entrance. The angle of inclination would naturally vary with the size of the building, but I have found it advantageous to make this incline very gradual in order that cars may be easily driven in and out. In the portion of the driveway extending from the entrance along the wall 10 there is a rise of eight feet and a like rise takes place in the portion of the driveway extending along the rear wall. This amount of rise is based on the assumption that the height of the first story is sixteen feet, so that with the rise described the driveway will have reached the height of the second story when it turns forwardly along the wall 11. The portion of the driveway along the walls 8 and 11 is in the present embodiment constructed horizontal. The rise of the driveway from the second to the third floor takes place in the second convolution along the walls 10 and 9, so that the third floor is reached when the driveway again turns towards the front. Successive rises take place between each of the floors with which the driveway communicates. It would prob-

ably be necessary to provide a rise in the driveway between the second and third floors, and also between the third and fourth floors, so that the driveway would be at the same height as the fourth floor when it turns forwardly along the wall 11. The portion of the driveway along the walls 8 and 11 is in the present embodiment constructed horizontal. The rise of the driveway from the second to the third floor takes place in the second convolution along the walls 10 and 9, so that the third floor is reached when the driveway again turns towards the front. Successive rises take place between each of the floors with which the driveway communicates. It would prob-

ably not be practical to continue the driveway above the sixth floor.

A parking strip 13 is provided along the outer edge of the driveway so that cars may be parked at any point along this driveway without interfering with the movement of cars therein. The paths to be followed by the automobiles in entering and leaving are indicated by lines in Fig. 2, and at the front corner 14 I have provided sufficient space to permit cars to turn around. The courses of the cars in entering and leaving the building may be marked by painted lines on the floors of the driveway. A partition 15 extends longitudinally of the inner edge of the driveway and separates the area devoted to stores or offices from this driveway. The building in the present embodiment is provided with an inner wall 16 forming a central court, and the space between the partition 15 and this wall may be subdivided in any suitable manner. All offices or stores within this area would have their entrances on the driveway and portions of the partition may be constructed of glass to provide show-windows in case the area within this partition is to be utilized for stores.

A portion of the lower or street floor of the building has been separated from the rest of the building by partition 17 to form a separate entrance hall at 18 communicating with the elevators 19 serving the seventh and higher floors. Elevators 20 are provided to take care of the second to the sixth floors.

In the present embodiment, the first floor of the building has been designed for use as a single store, and the space beneath the first rise of the driveway, following the wall 10, could be utilized for storage purposes. The portion of the driveway along the rear wall would be sufficiently raised above the store floor to make it available for general merchandising, as it is eight feet at its lowest and sixteen feet at its highest point. A skylight of the usual type would be constructed over the portion of the store beneath the court. The stores on the second and succeeding floors facing the driveway at the rear of the building would have their floors disposed relative to the incline of the driveway as is indicated at 21, and the same would be true of the stores facing the wall 10 on these floors.

It will thus be seen that a car may be driven into the building on the driveway and parked on any convenient floor. The position of the entrance to the driveway and the direction of the convolutions would naturally depend upon the location of the building relative to the street and adjacent buildings, for it is desirable to utilize as far as possible for the inclination of the driveway, the sides of the building having blank walls. It will be readily evident that the rise of the driveway may take place wholly along one side of the building or may be continuous for an entire convolution, depending upon the type of building and the particular use for which it is intended.

I am aware that many changes might be made in the construction and arrangement as described without departing from the spirit of my invention, and I reserve the right to make all such as fairly fall within the scope of the following claims.

I claim:

1. A building having an outer wall, an inner wall, an inclined winding driveway between said walls, a parking space along said driveway and a series of enclosures or rooms formed along said driveway and communicating therewith.

2. A building having an outer wall, an inner wall, an inclined winding driveway between said walls, a series of partitions forming with one of said walls a series of rooms along said driveway and communicating therewith and a parking space formed along said driveway adjacent the other wall.

3. A building having an enclosing wall, an inclined winding driveway within said building, a series of enclosures or rooms along said driveway and communicating therewith, and a parking space for vehicles along portions of said driveway opposite said rooms.

4. A building having an outer wall, an inner wall forming a well open at the top, a winding driveway between said inner wall and said outer wall, and a partition extending longitudinally of the inner edge of said driveway and adjacent thereto to form an enclosure between said driveway and said inner wall, said walls being uniformly spaced throughout their height.

HOWARD P. STURGES.
